DESIGN FOR A SUGAR BOWL

William E. Mackelfresh, Jr., Chicago, Ill., assignor to Owens-Illinois Glass Company, Toledo, Ohio, a corporation of Ohio

Application June 9, 1937, Serial No. 69,765

Term of patent 7 years

To all whom it may concern:

Be it known that I, William E. Mackelfresh, Jr., a citizen of the United States, residing at Chicago, in the county of Cook and State of Illinois, have invented a new, original, and ornamental Design for a Sugar Bowl, of which the following is a specification, reference being had to the accompanying drawing, forming a part thereof.

In the drawing:

Fig. 1 is a side elevational view of a sugar bowl showing my new design.

Fig. 2 is a top plan view thereof.

Fig. 3 is an elevational view taken at a right angle to Fig. 1.

I claim:

The ornamental design for a sugar bowl, substantially as shown.

WILLIAM E. MACKELFRESH, JR.
